BLADE ADJUSTING MEANS FOR SAFETY
RAZORS

Harry B. Carter, Austin, Tex.

Application August 6, 1951, Serial No. 240,557

2 Claims. (Cl. 30—57)

1

My invention relates to blade adjusting means for safety razors of the type forming the subject matter of my U. S. Letters Patent No. 2,482,152, dated September 20, 1949, and over which the instant invention is designed as an improvement.

The primary object of my invention is to provide in a safety razor in which the blade, guard, and holder are tiltable as a unit to vary the shaving angle of the blade, improved means for variable tilting those parts and locking the same in tilted position to the handle of the razor, and providing for adjustment of the guard relative to the edge of the blade in every tilted position of the blade, guard, and holder.

Another object is to provide for accomplishing the above by simply constructed inexpensive means which will not materially increase the cost of manufacture of the razor.

Other and subordinate objects, within the purview of my invention, together with the precise nature of my improvements will be readily understood when the succeeding description and claims are read with reference to the drawings accompanying and forming part of this specification.

In said drawing:

Figure 1 is a view in side elevation of a safety razor embodying my invention;

Figure 2 is a view in front elevation;

Figure 3 is a view in longitudinal section taken on the lines 3—3 of Figure 2;

Figure 4 is a fragmentary view in longitudinal section taken on the line 4—4 of Figure 1;

Figure 5 is a fragmentary view partly in side elevation and partly in longitudinal section, and

Figure 6 is a view in perspective of the guard and holder drawn to a larger scale.

Referring to the drawing by numerals, the type of safety razor with which my improvements are concerned includes a cylindrical handle 5 provided at its front end with a U-shaped extension yoke 6 including resilient side legs 7 formed with terminal apertures 8. The blade 9 is pivoted for tilting adjustment in the yoke 6 between the legs 7 by end trunnions 11 on said blade adapted to be entered in the apertures 8 by springing the legs 7 apart. The blade 9 rests upon a toothed backing guard 12 having a central transverse countersink 13 therein and a central transverse slot 14 in the countersink for a purpose presently seen. The guard 12 fits in and is backed by a relatively narrow U-shaped holder 15 having right angled end legs 16 adapted to fit between the legs 7, said guard being adjust-

2

able transversely of the holder 15 and transversely of the cutting edge of the blade 9 and secured to said holder 15 in transversely adjusted position by a clamping screw 17 extended through a central hole 18 in the holder 15 and through the slot 14 with a flat head 19 thereon fitting in the countersink 13, said screw having a wing nut 19' thereon in the back of the holder 15.

According to my improvements, the legs 16 of the holder 15 are each provided with a slot 20 at right angle to the plane of the holder for straddling the trunnions 11 and so that said holder, together with the guard 12 clamped thereto, may be positioned in the yoke 6 and thrust forwardly of the handle 5 to enter the legs 16 between the ends of the blade 9 and the legs 7 and also enter the trunnions 11 in the slots 20 with the guard 12 engaging the blade 9. The holder 15 is thus positioned in the yoke 6 and is pivotally mounted on the trunnions 11 for tilting about said trunnions, together with the guard 12, to tilt the blade 9 about its pivotal axis into different shaving positions.

Means are provided, in accordance with my invention, for locking the blade 9, guard 12, and holder 15 in different adjusted tilted positions and the guard 12 engaged with the blade 9 and which will now be described. A handle forming lever 25, integral with the guard 12, extends from the rear edge and center of said guard in the rear of the yoke 6 and handle 5 to ride alongside the same and terminates in a right angle free end, or lug 26 fitting in a transverse slot 27 formed in the front end portion of a handle 5. The free end 26 frictionally engages the bottom of the slot 27 so as to maintain the guard 12 engaged with the blade 9.

The handle 5 is provided with a threaded, axial bore 28 in its rear end, and with an axial counter bore 29 extending from the bore 28 to the slot 27. A locking pin 30 is threaded into the bore 28 with a reduced front pin section 31 fitting in the counter bore 29 for locking engagement with the free end 26 of the lever 25. A suitable finger grip knob 32 is provided on the outer end of the pin 30. The free end 26 is provided with a hole 33 therein and the pin may be adjusted to extend the section 31 through said hole and into a socket 34 in the handle 5 to lock the lever 25 with the blade 9 tilted at a shaving angle suitable for most users. However, by withdrawing the pin 30, the lever 25 may be swung to tilt the blade 9 at other angles, in a manner which will be clear, and the pin 30 then adjusted to clampingly engage the section 31 with the free end 26 to lock

said lever 25 and the blade 9 in the selected position of adjustment. The lever 25 is preferably of zig-zag form longitudinally to position its free end 26 close to the handle 5.

As will now be seen, the blade 9 may be tilted into a number of angular shaving positions in the yoke 6 by means of the lever 25 and locked in such positions by means of the lever 25 and pin 30, and in any tilted position of the blade 9, the wing nut 19 may be loosened and the guard 12 adjusted relative to the edge of the blade 9 and clamped into adjusted position by tightening said wing nut.

The foregoing will, it is believed, suffice to impart a clear understanding of my invention, without further explanation.

Manifestly, the invention, as described, is susceptible of modification, without departing from the inventive concept, and right is herein reserved to such modifications as formed in the scope of the appended claims.

Having described my invention, what is claimed as new is:

1. A safety razor including a handle having a front end yoke, a blade in said yoke having end trunnions pivoted to said yoke for tilting of said blade in the yoke, a guard backing said blade, means pivotally connecting said guard to said trunnions for tilting to tilt said blade, a lever on said guard for tilting the same, and means to lock the lever to the handle in the different tilted po-

sitions of the guard comprising an axial pin threaded into said handle, and a slot in said handle receiving one end of said lever and into which the pin is adjustable for clamping engagement with said end of the lever.

2. A safety razor including a handle having a front end yoke, a blade in said yoke having end trunnions pivoted to said yoke for tilting of said blade in the yoke, a guard backing said blade, means pivotally connecting said guard to said trunnions for tilting to tilt said blade, a lever on said guard for tilting the same, and means to lock said lever to said handle in the different tilted positions of said guard comprising a pin threaded into said handle, and a slot in said handle receiving one end of the lever and into which the pin is adjustable into clamping engagement with said end of the lever, said end of the lever being provided with an opening therein into which said pin is adjustable to lock the lever in one tilted position of said guard.

HARRY B. CARTER.
